Primary Examiner — Ania Aman(74) *Attorney, Agent, or Firm* — Buchanan Ingersoll & Rooney PC(57) **CLAIM**

The ornamental design for a three-wheeled electric vehicle, as shown and described.

DESCRIPTION

FIG. 1 is a front perspective view of a three-wheeled electric vehicle showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines illustrate portions of the three-wheeled electric vehicle that form no part of the claimed design. The dash-dotted lines denote the boundary of the claim and form no part of the claimed design.

1 Claim, 8 Drawing Sheets(56)
